UNITED STATES PATENT OFFICE

148,939

DESIGN FOR A FORK FOR BICYCLES AND
VELOCIPEDES

Edward D. Martin, Milwaukee, Wis.

Application July 20, 1946, Serial No. 131,762

Term of patent 7 years

(Cl. D90—9)

To all whom it may concern:

Be it known that I, Edward D. Martin, a citizen of the United States and resident of Milwaukee, in the county of Milwaukee, and State of Wisconsin, have invented a new, original, and ornamental Design for a Fork for Bicycles and Velocipedes, of which the following is a specification, reference being had to the accompanying drawing, forming part thereof.

Figure 1 is a side elevational view of the bicycle and velocipede front fork assembly showing my new design.

Figure 2 is a front elevational view of the fork.

Figure 3 is a rear elevational view of the fork.

Figure 4 is a top plan view of the fork.

I claim:

The ornamental design for a fork for bicycles and velocipedes, as shown.

EDWARD D. MARTIN.
